UNITED STATES PATENT OFFICE.

JOHN E. HUNTER, JOSEPH R. RAHISER, AND ENOS BARKEY, OF EVANS CITY, PENNSYLVANIA.

REAMING ATTACHMENT FOR PIPE-CUTTERS.

No. 802,512.

Specification of Letters Patent.

Patented Oct. 24, 1905.

Application filed June 21, 1905. Serial No. 266,307.

To all whom it may concern:

Be it known that we, JOHN E. HUNTER, JOSEPH R. RAHISER, and ENOS BARKEY, citizens of the United States, residing at Evans City, 5 in the county of Butler, State of Pennsylvania, have invented certain new and useful Improvements in Reaming Attachments for Pipe-Cutters; and we do hereby declare the following to be a full, clear, and exact description of the 10 invention, such as will enable others skilled in the art to which it appertains to make and use the same.

This invention relates to pipe-cutting machines, and more particularly to attachments 15 therefor, and has for its object to provide an attachment for smoothing the inside surface of cut pipe, the attachment being arranged to take the place of the cut-off-block cap of the machine.

20 Another object is to provide an attachment of this kind which will be extremely simple and which may consequently be manufactured at a low figure.

Other objects and advantages will be apparent 25 from the following specification, which describes an embodiment of the present invention.

In the drawings forming a portion of this specification, and in which like numerals of 30 reference indicate similar parts in the several views, Figure 1 is a front view of the die-head of a pipe-cutting machine, the present invention being shown thereupon. Fig. 2 is a top plan view of the complete machine, the present invention being shown in use. Fig. 3 is a 35 detail perspective view of the present invention removed from the machine. Fig. 4 is a side elevation of a portion of the machine, showing the present attachment in use.

40 Referring now to the drawings, there is shown a pipe-cutting machine 5, including a frame 6, at one end of which there is a revolving head-stock 7, the frame 6 including a bed upon which there is mounted a carriage 8, 45 slideable toward and away from the head-stock. The carriage 8 carries a die-head 9, provided with removable thread-cutting jaws 10, and mounted in the carriage inwardly of the head 9 there is a transverse guide 11, upon which 50 there is slidably mounted a cut-off block 12, having a longitudinal recess 13 in its upper face, which extends transversely of the frame 6, and removably disposed in this recess there is a cut-off knife 14, which is directed in-

wardly and which is adapted for engagement 55 of its cutting end with a pipe engaged in the head-stock 7, a hand-screw 15 being connected with the block 12 for movement of the latter into the desired position.

In the place of the usual cut-off-block cap 60 the present attachment (indicated at 16) is disposed upon the cut-off block and closes the upper side of the recess 13. This attachment comprises an elongated plate, having openings 17 adjacent to its ends, in which the usual 65 attaching-bolts 18 are received, and at the side of the plate which is directed toward the head-stock 7 fingers 19 are formed at its ends and extend in the direction of the head-stock. The inner faces of these fingers are beveled 70 toward their free ends and are also beveled oppositely from the upper to the lower faces of the fingers to form inwardly-directed cutting edges 20 and 20', respectively, the former lying at the upper and the latter at the lower 75 face of the plate. The adjacent side edge 21 of the plate is also beveled adjacent to the fingers, as shown at 22 and 23, these bevels meeting the inner ends of the beveled inner faces of the fingers, so that these bevels 22 80 and 23 are directed one upwardly and one downwardly when the plate is in position. It will thus be seen that after a pipe has been cut the cut-off block 12 may be moved to bring the finger 19, lying at the inner end of 85 the attachment, into the end of the section of pipe held in the head-stock 7 and to bring the cutting edge of this finger against the roughened inner surface of the pipe, when the rotation of the pipe will cause this cutting edge 90 to smooth the pipe. After one of the cutting edges has been dulled, the attachment may be shifted end for end to bring the other finger into operative position.

What is claimed is—

1. The combination in a pipe-cutting machine including a cut-off block having a recess in its top adapted for the reception of a tool, of a plate disposed upon the cut-off block to close the recess, said plate having fingers 100 thereon provided with cutting edges.

2. The combination in a pipe-cutting machine including a pipe-receiving stock and a shiftable cut-off block having a tool-receiving recess therein, of a plate secured upon the 105 block to cover the recess, said plate having fingers at its opposite ends provided with oppositely-disposed cutting edges said plate be

ing movable with the cut-off block to bring one of its cutting edges into engagement with a pipe engaged in the stock to smooth the pipe, said plate being shiftable end for end to bring its other finger into position for engagement of the pipe.

3. A smoothing attachment for pipe-cutting machines comprising a plate having fingers extending from its opposite ends at one side of the plate, said fingers having cutting edges at opposite faces of the plate, said plate having openings therein adapted for the reception of the securing-screws of a cut-off block.

4. An attachment of the class described com-

prising a plate having openings therein adapted for the reception of attaching devices and having fingers extending from one of its side edges, said fingers lying in spaced relation and having inwardly-directed cutting edges located at opposite faces of the plate. 15

In testimony whereof we affix our signatures in presence of two witnesses.

JOHN E. HUNTER.
JOSEPH R. RAHISER.
ENOS BARKEY.
